Des. 194,337

Patented Jan. 1, 1963

194,337

BACK SCRATCHER

Edward Greeman, 111 Wood Hollow Lane, New Rochelle, N.Y.; Alan Bickler, 3439 3rd St., Oceanside, N.Y., and Jack Sherman, 61 Shelter Hill Road, Plainview, N.Y.

Filed June 15, 1961, Ser. No. 65,606

Term of patent 3½ years

(Cl. D86—10)

FIG. 1 is a perspective view of a back scratcher showing our new design;

FIG. 2 is a front elevational view; and

FIG. 3 is a bottom plan view.

We claim:

The ornamental design for a back scratcher, as shown.
